PATTERN SELECTING MECHANISM

George Herbert White, Hartford, Conn., assignor
to Chester A. Macomic, Chicago, Ill.

Application January 3, 1933, Serial No. 649,801

18 Claims. (Cl. 276—13)

My invention relates to improvements in pattern selecting mechanism and is especially adapted for use in connection with type casting and type setting machines wherein it is desired to add 5 just or position a series of lines of characters either in the form of a matrix or printing strip with the characters thereon or in the form of assemblies of matrices or type characters in line in response to some other selecting mechanism. 10 Among the objects of my invention are to provide a driving and releasing mechanism so that the separate strips or lines of characters may be propelled forward into the working position, released when they reach that position, may again 15 be picked up and returned for distribution. Another object is to provide in combination with a longitudinally movable strip, a yieldingly releasable drive head. Another object is to provide a flexible connection for the drive head between it 20 and each strip so that strips may be compressed or released and so slightly moved or displaced laterally without interfering with the driving relation. Other objects of the invention will appear from time to time throughout the specification 25 and claims.

My invention is illustrated more or less diagrammatically in the accompanying drawings, wherein—

Figure 1 is a detail side elevation showing part 30 of the machine with which it is to be used;

Figure 2 is a longitudinal section through the machine with parts in elevation;

Figure 3 is a similar section showing the parts in a slightly different relative position;

Figure 4 is a plan view;

Figure 5 is a detail in part section of the drive head;

Figure 6 is a section along the line 6—6 of Figure 5;

Figure 7 is a detail of the spring supported hook;

Figure 8 is an enlarged section along the line 8—8 of Figure 5;

Figure 9 is an enlarged section along the line 45 9—9 of Figure 2.

Like parts are indicated by like characters throughout the specification and claims.

It will be understood that the invention here in question is only one of a series of cooperating 50 elements are united and cooperating to provide an operating device and I have illustrated only so much of the operating device to properly understand the relation of the invention here in question with the whole machine.

55 A is the main frame; A¹ an upright frame mem-

ber projecting therefrom. A² is a pattern selecting frame and A³ is a typewriter supported thereon. The only part of the pattern selecting mechanism with which we are here concerned is the pattern bed A⁴ and the so-called matrix bed A⁵. 60

Pins A⁶ in the pattern bed are adapted to be longitudinally displaced in a direction transverse to the bed by means not here shown controlled and operated by the typewriter A³. This pattern bed comprises a plurality of parallel intersecting strips A⁷ A⁸ which form rectangular cells, each cell containing a spring member A⁹ so that each pattern pin A⁶ is guided in its longitudinal motion and held in proper position by spring friction. The strips A⁸ project below the honeycomb of the bed to provide a plurality of parallel guide channels whose importance will herein-after appear. 70

The matrix bed A⁵ is a flat smooth plate. On 75 it are mounted for longitudinal movement a plurality of matrix strips B. As indicated, these strips carry preferably at the points B¹ in intaglio, characters from which type is to be cast but the reverse might be the case and printing characters themselves might be disposed on the faces of the strip or separate type slugs or separate intaglio strips might be substituted for the strip as the case may be without departing from the spirit of my invention. Each of these strips B 80

terminates in a relatively thin flexible strip B² narrower than the strip, the strip being recessed at B³ so that the overall width of the strip and spring is only the width of the strip. This spring is a little shallower than the strip so that it does 85 not rest upon the matrix bed. At the forward end of the spring strip is mounted a guide plate B⁴ spaced from the spring plate so that the overall width of guide plate and spring is substantially equal to the overall width of the strip. This 90

guide member projects upwardly beyond the strip as indicated at B⁵ to form a guide section which travels between each pair of strips A⁸ and guides the flexibly mounted drive head in its movement along the pattern bed. The pattern bed may under some circumstances have an up and down movement, the width of these strips being so related to the guide strip so that no matter what the position of the pattern bed, the guide member is always held between the two strips A⁸. The guide plate B⁴ is cut away longitudinally as indicated to form a hook pocket B⁶ where it is adapted to engage a stop pin A⁶. The guide plate B⁴ and the spring are held together by rivets B⁷ B⁸, and spot welding. 95

100 It will be understood that the invention here in question is only one of a series of cooperating elements are united and cooperating to provide an operating device and I have illustrated only so much of the operating device to properly understand the relation of the invention here in question with the whole machine. 105 A is the main frame; A¹ an upright frame mem-

C is a latch. It has at its rear or in-most end, a notch C¹ having a cylindrical bottom. It has on its underside two shoulders C² C³ and a curved spring seat C⁴. C⁵ is a spring of such length that it fits snugly between the shoulders C² C³ when it is straight and so related that it may be bent to conform to the seat C⁴, the spring being held in place because the thickness of the spring and the latch produces a snug working fit in the pocket 5 B⁶. C⁶ is a stop surface on the opposed side of the latch adapted to engage the upper side of the pocket. C⁷ is a hook on the end of the latch. It has an inclined surface C⁸, an inclined surface C⁹, an inclined surface C¹⁰.
 15 The latch cooperates with a drive bar D which bar is mounted on a sliding carriage means D¹ on opposed sides of the machine which sliding carriage means are adapted to be moved back and forth by links D² on levers D³ driven by a crank 20 arm D⁴ to cause a back and forth reciprocation of the bar D. This bar D has on its under surface a notch D⁵ slightly inclined across the body of the machine. This notch has an inclined surface D⁶ adapted to cooperate with the inclined surface 25 C⁹ on the latch; and inclined surface D⁷ adapted to cooperate with the surface C⁸ on the latch and so positioned that when the bar D is in engagement with the guide plate B⁴, there is clearance between the surfaces D⁷ and C¹⁰. The latch is held in place by engagement between the notch C¹ 30 and the rivet B⁸ and by engagement between the spring C⁵ and the rivet B⁷, the spring being slightly flexed normally tends to hold the latch in the position shown in Figure 5. Figure 2 shows the 35 position of the parts when the bar D is going down, drawing the matrix strips after it. It is shown when the guide member has just engaged the stop A⁶. Further movement of the bar D causes the latch to assume the dotted line position 40 because the two inclined surfaces result in a camming action compressing the spring. On the return motion, the member D will be moved backward until the surface D⁷ will have a camming engagement with the surface C⁸, depress the latch and snap back into position going on to the return driving position shown in Figure 3.
 45

The notch D⁵ is diagonal so that even if the same character on each matrix were to be released, still the release would be progressive and thus not overload the mechanism.

The latch is assembled by first putting the spring C⁵ in the position shown in Figure 7. Then inserting the spring and latch through the front of the pocket C⁵, compressing the spring into the dotted line position shown in Figure 5, pushing it beneath the rivet B⁸ and then allowing the spring to force it up into engagement. Its disassembly is the reverse of this. Thus the spring C⁵ serves both as the release spring for the latch and as a retaining spring to hold the parts in proper working relation.

I claim:

1. A propeller mechanism for reciprocating members of a character selecting mechanism and the like comprising a longitudinally movable member, a flat spring mounted on the end thereof, a combined latch and guide head mounted on the spring.

2. A propeller mechanism for reciprocating members of a character selecting mechanism and the like comprising a longitudinally movable member, a flat spring mounted on the end thereof, a combined latch and guide head mounted on the spring, there being a pocket in said head

and a spring held latch contained within said pocket.

3. A propeller mechanism for reciprocating members of a character selecting mechanism and the like comprising a longitudinally movable member, a flat spring mounted on the end thereof, a combined latch and guide head mounted on the spring, there being a pocket in said head and a spring held latch contained within said pocket, there being a pair of cross members in the pocket, the latch being notched to engage one of said cross members, a spring interposed between the latch and the other cross member whereby the notch on the latch is held in engagement with the cross member.

4. A propeller mechanism for reciprocating members of a character selecting mechanism and the like comprising a longitudinally movable member, a flat spring mounted on the end thereof, a combined latch and guide head mounted on the spring, there being a pocket in said head and a spring held latch contained within said pocket, there being a pair of cross members in the pocket, the latch being notched to engage one of said cross members, a spring interposed between the latch and the other cross member whereby the notch on the latch is held in engagement with the cross member, the spring being adapted to yield to permit releasing of the latch in a direction generally transverse to the line of travel of the head.

5. In a selecting mechanism, a supporting bed having a relatively smooth surface, a plurality of elements adapted to move therealong, guide fins projecting upwardly from said elements, flexible connections between each element and its guide fin and a track constraining each guide fin to parallel movement.

6. In a selecting mechanism, a supporting bed having a relatively smooth surface, a plurality of elements adapted to move therealong, guide fins projecting upwardly from said elements, flexible connections between each element and its guide fin and a track constraining each guide fin to parallel movement, a stop member located within said track adapted to engage and stop the movement of the guide fin.

7. In combination, a relatively elongated flat strip recessed at one end, a thin spring mounted in said recess and rigidly attached to the strip, the overall thickness of spring and strip being substantially equal to the normal thickness of the strip, a guide and latch head including the free end of the spring and a separate plate attached thereto, which plate has a guide fin extending upwardly above the strip.

8. In combination, a relatively elongated flat strip recessed at one end, a thin spring mounted in said recess and rigidly attached to the strip, the overall thickness of spring and strip being substantially equal to the normal thickness of the strip, a guide and latch head including the free end of the spring and a separate plate attached thereto, which plate has a guide fin extending upwardly above the strip, there being a pocket formed between the spring and plate, a yieldably releasable latch contained within said pocket.

9. A spring release latch comprising a pocket, a plurality of cross members extending therethrough, a latch in the pocket interposed between the cross members, the latch being notched adjacent one end to engage one of them, the opposed edge of the latch being curved to provide a spring clearance, a straight spring adapted normally to engage the latch adjacent each end
